EX

OR D 13,604

DESIGN FOR A STOVE.

Design No. 13,604, dated February 6, 1883.

UNITED STATES PATENT OFFICE.

WALTER P. WARREN, OF TROY, NEW YORK, ASSIGNOR TO THE FULLER & WARREN COMPANY, OF SAME PLACE.

DESIGN FOR A STOVE.

SPECIFICATION forming part of Design No. 13,604, dated February 6, 1863.

Application filed December 8, 1882. Term of patent 7 years.

To all whom it may concern:

Be it known that I, WALTER P. WARREN, of the city of Troy, county of Rensselaer, and State of New York, have invented a new and useful Improvement in Ornamental Designs for Stoves, of which the following is a specification.

My invention relates to the ornamentation of stoves and ranges and the manner of producing an ornament for that purpose, which may be applied to any part of a stove or range that is suitably shaped to receive it, although more particularly adapted to the ornamentation of the panels formed in stove and range doors.

My invention of a design for such a stove ornament, and as it is shown in the annexed engraving, forming a part of this specification, consists of the diamond-form ornament F, in its composition consisting of the sides a' the beveled border upon its relief face (indicated at a²) for the insertion of words or letters, the central radiate ornamentation, n, and the diagonal bar S, in which to display a word or letters.

While I have shown the words "everlasting," "economical," "elegant," and "efficient," as displayed in the beveled border, and the word "stoves" in the diagonal bar S of the ornament, other words and ornamentation producing the same effect may be used in place of the foregoing, if desired.

Having thus described my invention of a design for a stove ornament, what I claim, and desire to secure by Letters Patent, is—

The design for the stove ornament F, in combination, consisting of the diamond form 35 inclosed by the sides a' a' a' a', the beveled border a², the central radiate ornamentation, n, and the horizontal bar S, as shown and described.

Signed at Troy, New York, this 20th day of 40 November, 1882.

WALTER P. WARREN.
